United States Patent Office

Des. 219,504
Patented Dec. 22, 1970

219,504

BOTTLE

Emanuel M. Terner, Oakhurst, N.J., assignor to Midland Glass Company, Inc., Cliffwood, N.J., a corporation of Delaware

Filed Sept. 26, 1969, Ser. No. 19,305

Term of patent 14 years

Int. Cl. D9—01

U.S. Cl. D9—161

FIG. 1

FIG. 2

FIG. 3

FIG. 1 is an elevational view of a bottle showing my new design, the opposite side being substantially the same in appearance as the side shown;

FIG. 2 is a top plan view; and

FIG. 3 is a bottom plan view thereof.

I claim:

The ornamental design for a bottle, substantially as shown and described.
